UNITED STATES PATENT OFFICE

MASON J. SMITH, OF KANSAS CITY, MISSOURI

MOUTHPIECE SLEEVE

Application filed March 25, 1931. Serial No. 525,120.

This invention relates to a new article of manufacture formed particularly for combination with mouth pieces and especially the mouth pieces of pipes, cigar and cigarette holders. The primary object of the invention is to provide an article which fully protects the mouth piece with which it is used, as well as the teeth of the smoker.

It is well known that pipe smokers have a tendency to grip the mouth piece of the pipe at times, which grip is severe enough to grind away both the teeth and the pipe stem. Through the use of a device contemplated by this invention, such grinding or injurious action might be obviated. In view of the above, therefore, this invention further contemplates the use of a pliable protector for mouth pieces which is constructed to present a cushion interposed between the teeth of the smoker and the hard surface of the mouth piece of his pipe, cigar or cigarette holder.

Specific objects of the invention including the manner of making a mouth piece sleeve in accordance with this invention will appear during the course of the following specification, referring to the accompanying drawings, wherein:

Figure 1 is a perspective view of a smoker's pipe equipped with a mouth piece sleeve made in accordance with this invention.

Fig. 2 is an enlarged vertical longitudinal section through the attachment and the adjoining portion of the smoker's pipe.

Fig. 3 is a vertical cross section of the same taken on line III—III of Fig. 2.

Fig. 4 is a broken side elevation of a mouth piece sleeve before its attachment to a mouth piece.

Fig. 5 is a perspective view of a cigar holder having the protecting sleeve affixed thereto, and,

Fig. 6 is a view showing a mouth piece sleeve attached to a cigarette holder.

In specifically describing the invention as it is embodied in a protecting sleeve as illustrated in the drawings, like reference characters will be used to designate similar parts throughout the several views. Materials from which the protector is made might include any compositions which have the in-

herent quality of being pliable enough to conform to the contour of the mouth piece with which it is used, yet tough enough to withstand the grip imposed thereon by the teeth of the user.

Preferably, the mouth piece sleeve consists of a single piece of pliable material molded or otherwise formed to present a sleeve 8 having an inwardly and laterally disposed flange 10 at each end respectively thereof, which engages the mouth piece 12 of either the smoking pipe, cigar holder or cigarette holder, as illustrated in the drawings.

Reference to Fig. 2 readily indicates that flanges 10 maintain the wall of sleeve 8 between flanges 10 in spaced relation to the mouth piece 12 so that besides the pliability of the sleeve, a cushion is presented which absorbs any shocks which might normally be set up between mouth piece 12 and the teeth of the smoker.

This last mentioned feature being the salient object of the invention, the same is further insured by building into the device a plurality of flutes 14 which may extend along the inner wall of sleeve 8 in any direction, but which preferably are formed longitudinally of sleeve 8 and to terminate inwardly from the ends of the sleeve, whereby they will not affect a positive grip which flanges 10 have established. With this fluted construction, the space between mouth piece 12 and sleeve 8 is not regular, but is increased at more or less regular intervals throughout the area of the inner wall of sleeve 8.

To further strengthen sleeve 8 and form more or less of a limiting zone, an outwardly directed bead 16 is molded at each end respectively of sleeve 8. As indicated in the drawings, both flanges 10 and beads 16 are continuous, and their combined thickness, together with the thickness of sleeve 8, presents a structure which is strong at the points necessary, yet pliable and agreeable along the zone of grip where such qualities are most desirable.

Modifications as to specific form, contour, size and material might be made when making a mouth piece sleeve in accordance with this invention without departing from the

broad concepts thereof or the scope of the appended claims.

What is claimed as new and desired to be secured by Letters Patent is:

- 5 1. As a new article of manufacture, a protector formed to engage a mouth piece, comprising a sleeve of pliable material; and an inwardly and laterally disposed flange at each end respectively of said sleeve whereby
- 10 10 to maintain the sleeve wall in spaced relation to the mouth piece intermediate said flanges.
- 15 2. As a new article of manufacture, a protector formed to engage a mouth piece, comprising a sleeve of pliable material; an inwardly and laterally disposed flange at each end respectively of said sleeve; and an outwardly directed bead at each end respectively of said sleeve.
- 20 3. As a new article of manufacture, a protector formed to engage a mouth piece, comprising a sleeve of pliable material; means to maintain the major portion of the sleeve wall in spaced relation to the mouth piece; and a plurality of flutes formed in that portion of the sleeve wall held in spaced relation to the mouth piece.
- 25 4. A mouth piece sleeve of pliable material formed to present a sleeve; and a plurality of longitudinal flutes along the inner annular wall of said sleeve, said flutes terminating inwardly from the ends of said sleeve.
- 30 5. A mouth piece sleeve of pliable material formed to present a sleeve; a plurality of longitudinal flutes along the inner wall of said sleeve; and an inwardly disposed flange at each end respectively of said sleeve, said flutes terminating at said flanges.
- 35 6. A mouth piece of pliable material formed to present a sleeve; a plurality of flutes along the inner wall of said sleeve; an inwardly disposed flange and an outwardly disposed bead at each end respectively of said sleeve.
- 40 45 In testimony whereof, I hereunto affix my signature.

MASON J. SMITH.
